UNITED STATES PATENT OFFICE.

PERLEY H. FULLER, OF AUBURN, MAINE.

OIL-BURNER.

1,297,137.

Specification of Letters Patent.

Patented Mar. 11, 1919.

Application filed October 11, 1918. Serial No. 257,705.

To all whom it may concern:

Be it known that I, PERLEY H. FULLER, a citizen of the United States, residing at Auburn, in the county of Androscoggin and 5 State of Maine, have invented certain new and useful Improvements in Oil-Burners, of which the following is a specification.

My invention relates to oil burners designed particularly to burn kerosene oil in 10 ranges, furnaces and other heaters.

In the type of burners to which my invention belongs, the oil is fed to the burners under a high pressure and passes through a heated vaporizing chamber which is 15 heated by the flames of the burner. The vapor is discharged through a small discharging nozzle into a mixing chamber where air and vapor are commingled and burned in an intense flame.

20 The object of my invention is to construct the burner with a double outlet so that as each outlet discharges its flame it will come into heating contact with the vaporizing chamber of the other portion of 25 the burner. Burners of this type have a tendency to fill the vaporizing chamber with carbon deposit which is one of the products of the decomposition of the oil. I have found that the introduction of water vapor 30 into the vaporizing chamber checks this tendency and prevents the carbon from depositing.

A further object of my invention therefore is to provide means of introducing 35 water vapor into the vaporizing chamber without the expensive apparatus which would be necessary to force it in under pressure.

For the purpose of introducing the water 40 into the vaporizing chamber, I form one of the walls of said chamber of refractory and absorbent material as asbestos board and provide means of bringing a continuous supply of water into contact with the body of 45 the absorbent material outside of the chamber.

The capillary attraction carries the water through the pervious wall notwithstanding the internal pressure in the chamber and the 50 water vapor is taken up and mixed with the hydrocarbon vapor modifying the reactions within the vaporizing chamber and preventing the carbon deposits.

In the preferred embodiment of my invention, I make use of standard pipe fittings, but it is evident that a burner em-

bodying my invention may be built up in a variety of ways.

I have illustrated my invention in the accompanying drawing in which is shown a 60 burner suitable for a range or furnace and made up of standard fittings so that it may be easily and cheaply constructed.

Referring to the drawings,

Figure 1 is a side elevation.

65

Fig. 2 is a plan.

Fig. 3 is an end elevation with baffle plate removed and,

Fig. 4 is a section enlarged, the upper half being taken on the line 1—1 of Fig. 2 and 70 the lower half on 2—2 of Fig. 2.

In the drawings,

2 represents the central hub of a standard **T** in which is a suitable opening 3 connecting with a pipe through which the oil under 75 pressure is fed to the burner (see Fig. 3). In each of the lateral branches 5 and 6 of the **T**, I screw a short length of pipe 7 and 8 respectively and at the outer end of each of the pipes 7 and 8, I connect a return 80 bend. The return bend 9 connects with the pipe 7 and the return bend 10 connects with the pipe 8. In the outlet end of each return bend I screw a short section of pipe or tube 11 and 12, these tubes comprising the mixing 85 chambers of the burner where the air and vapor unite to form the flame which takes fire and burns after passing through the tube on the principle of the Bunsen burner. The two bends are turned away 90 from each other so that the outlet opening of each will be pointing in the opposite direction to the other and parallel therewith and so that the tubes 11 and 12 will lie side 95 by side, but discharging in opposite directions. In the outlet end of each of the bends I insert a vapor discharge nozzle 13, this nozzle being located inside of the inner end of the mixing tube. In each of the mixing tubes is cut an air inlet slot 15 and a ring 16 100 is designed to regulate the air supply. Each of the tubes 11 and 12 are left open at their outer ends so that the flame is discharged at the same time in two opposite directions at the opposite ends of the burner. The 105 flame produced by this burner, as will be seen, is a noiseless flame burning on the principle of the Bunsen burner since the vapor and air do not take fire to form the flame until they issue from the end of the mixing 110 tube when they have been thoroughly mixed.

The amount of air admitted and the diam-

eter of the tube with the pressure on the oil are such that this result is accomplished and a noiseless flame produced. Means are provided whereby these two oppositely moving 5 flames are deflected laterally and each brought into heating contact with the vaporizing chamber which supplies the other with vapor.

For this purpose I suspend a baffling plate 10 17 in front of the outlet of each of the tubes 11 and 12. Each of the baffle plates 17 is suspended from an arm 18 attached to a ring 19 which surrounds one of the pipes 7 and 8.

The baffle plate is pivoted to the arm 18 15 and is arranged at an angle which tends to deflect the flame against the adjacent return bend, the latter constituting a portion of the vaporizing chamber.

Under normal conditions the baffle plate 20 remains vertical, but when the flame is projected out with unusual pressure behind it, the baffle plate swings away from the end of the tube and the full heat of the flame is not projected against the return bend or vaporizing chamber.

It will thus be seen that the heat of the vaporizing chamber is always kept up by projecting against it the flame from the opposite discharge nozzle and overheating 30 is prevented by deflecting the flame as described.

Means are provided for introducing water vapor into the vaporizing chamber or a connecting chamber and against the internal 35 pressure which always exists in the chamber when in operation. For this purpose I introduce into one of the walls of the vaporizing chamber a diaphragm of refractory and absorbent material and provide means for 40 keeping said diaphragm continuously wet.

As here shown I screw into the lateral hub of the T 2, a short nipple 20 and on the outer end of the nipple I connect a flange 21.

To the face of the flange 21, I secure a 45 pair of disks 22 and 23 preferably formed of asbestos and these two disks are held against the flange 21 by an impervious plate 24. The disk 22 constitutes in effect a diaphragm interposed between the source of water supply and the interior of the vaporizing chamber the water continually passing inward through this diaphragm by capillary attraction against the internal pressure of the vaporizing chamber. The disk 23 may be 50 55 regarded as an auxiliary diaphragm as it retains a certain amount of the water.

The disks 22, 23 and 24 are secured to the flange 21 by suitable bolts 25.

The disks 22 and 23 are slightly separated 60 to form a thin water chamber and this water chamber is filled by a plurality of fine woven wire disks 26 which insure the distribution of the water.

At the upper end of the water chamber a 65 small aperture 27 is formed to receive the

water which is allowed to drip in through the pipe 28.

The pipe 28 connects with a water tank 30 and is controlled by a suitable valve 29.

The oil in the pipe 4 is connected with a 70 suitable source of oil supply under pressure and the oil supply is controlled by a valve 31.

While the burner is in operation, water is allowed to drip into the water chamber 27, it is distributed through the wire gauze 26 75 and absorbed by the asbestos disks 22 and 23.

The inner surface of the asbestos diaphragm is always exposed to the heat of the vaporizing chamber and the result is a constant evaporation of moisture from the said 80 surface.

This evaporation takes place regularly and supplies the heated hydro-carbon vapor with a large portion of water vapor and the result is a very hot flame and a burner which 85 will not deposit carbon in the vaporizing chamber.

For the purpose of preventing the vapor discharge nozzles from becoming obstructed by any carbon which may be formed in the 90 vaporizing chamber, I cover the inner end of the vapor discharge nozzle with a suitable wire gauze strainer 32 clearly shown in Fig. 1.

I find with a burner constructed on this 95 principle that while it does not prevent the formation of carbon in the vaporizing chamber, it allows the minute particles of carbon to pass off through the vaporizing nozzle without depositing on the walls of the chamber and this carbon is burned as a series of 100 sparks or very bright points in the flame of the burner.

I claim:

1. An oil burner having a pair of vaporizing chambers adjacent to each other, a vapor discharge nozzle connected with each of said vaporizing chambers, and a baffling plate for deflecting the flame from each nozzle into heating contact with the opposite 110 vaporizing chamber.

2. In a vaporizing oil burner, the combination of a T having an oil connection, a pipe connecting with each end of said T, a return bend at the outer end of each of said pipes, a vapor discharging nozzle at the outlet of each of said return bends pointing in parallel and opposite directions, and a baffle plate in front of each nozzle for deflecting the heat to the opposite return bend. 115 120

3. An oil burner having a pair of vaporizing chambers adjacent to each other, a vapor discharge nozzle connected with each of said vaporizing chambers and a baffle plate pivotally suspended in front of each 125 nozzle and arranged to throw the flame into heating contact with the other vaporizing chamber.

4. An oil burner including a vaporizing chamber one of the walls of which is formed 130

by a diaphragm of refractory and absorbent material, a flat thin water chamber being formed on the back face of said diaphragm and means for supplying water to said water chamber.

5. An oil burner including a vaporizing chamber one of the walls of which is formed of a diaphragm of refractory and absorbent material, a flat thin water chamber formed 10 on the back side of said diaphragm, a pervious filling for said water chamber for distributing the water and a water inlet for said water chamber.

6. An oil burner including a vaporizing chamber one of the walls of which is formed 15 of a main diaphragm of refractory and absorbent material, a like auxiliary diaphragm outside of said main diaphragm, said diaphragms being separated to form a water chamber, a pervious filling for said water chamber and an impervious outer covering 20 plate for confining the water.

7. An oil burner having a vaporizing chamber with an oil inlet, a pipe leading 25 from said vaporizing chamber, a collar on said pipe, a pair of disks of refractory and absorbent material secured to the outer surface of said collar said disks being slightly separated to form a thin water chamber, a 30 plurality of wire gauze disks filling said water chamber, an impervious disk outside of the absorbent disks for confining the water and means for introducing water into said water chamber.

35 8. In a vaporizing oil burner, the combi-

nation of a vaporizing chamber, an oil inlet duct therefor, a vapor discharge nozzle at each end of said chamber, a mixing tube for each nozzle, the nozzles and mixing tubes being each positioned to direct a flame in the 40 direction of the exterior portion of the opposite end of the vaporizing chamber.

9. In a vaporizing oil burner, the combination of a vaporizing chamber having an oil inlet therein, a vapor discharge nozzle at 45 each end of said chamber, a mixing tube for each nozzle and means for directing a portion of the flame from each mixing tube into heating contact with the exterior portion of the opposite end of said vaporizing chamber. 50

10. In a vaporizing oil burner, the combination of an externally heated oil vaporizing chamber, an oil supply duct connected therewith, a water vapor chamber having a wall composed of refractory and absorbent material, said water vaporizing chamber being directly connected with said oil vaporizing chamber and means for supplying water to 55 said absorbent material outside of said water chamber.

11. In a vaporizing oil burner, the combination of an open vaporizing chamber having a wall of refractory and fibrous material, the interior of said wall being exposed to the action of the vapor contained in said 60 chamber and means for supplying water to the outer portion of said wall.

In testimony whereof I affix signature.

PERLEY H. FULLER.
